UNITED STATES PATENT OFFICE.

JAMES T. RAY, OF CAMPBELL, TEXAS.

OIL HEATER.

Application filed May 31, 1923. Serial No. 642,649.

To all whom it may concern:

Be it known that I, JAMES T. RAY, a citizen of the United States, residing at Campbell, in the county of Hunt and State of Texas, have invented a new and useful Oil Heater, of which the following is a specification.

This invention relates to oil stove constructions and more particularly to a heating stove especially designed for burning crude oils.

The primary object of the invention is to provide a stove of this character wherein the oil fed to the burners may be accurately controlled and regulated.

Another object of the invention is to provide a stove having a plurality of independent oil feed pipes, the burners which are supported at the ends of the feed pipes being such as to eliminate the use of wicks or similar feeding means.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through a stove constructed in accordance with the invention;

Figure 2 is a side elevational view thereof;

Figure 3 is a sectional view taken on line 3—3 of Figure 2.

Figure 4 is a sectional view through one of the burners employed as a part of the stove construction.

Referring to the drawings in detail, the body portion of the stove is indicated generally by the reference character 5 and includes an outer wall 6 and an inner wall 7, the walls of the stove being constructed preferably of sheet metal. However it is to be understood that any suitable material may be employed in the construction of the stove without departing from the spirit of the invention.

As shown the walls 6 and 7 are substantially cone-shaped, each wall being formed with an upper curved portion 8 and a curved portion 9, the curved portions being

connected by the relatively straight walls 10, the outer curved wall 9 terminating in a relatively straight pipe 11 to permit the heat and products of combustion to pass from the stove.

The inner and outer curved walls 8 and 9 cooperate to provide chambers adapted to trap portions of the heat and products of combustion passing through the stove to cause the stove to become thoroughly heated, thereby increasing the heating qualities of the stove.

The lower portion of the stove is closed by the bottom wall 12 to which the walls 6 and 7 are bolted, as at 13, so that the wall 12 not only forms the bottom wall of the stove, but at the same time provides a support for the walls of the stove.

Supported adjacent to the stove at a point in proximity to the upper end thereof, are the oil tanks 14 that are held in suitable spaced relation with each other by means of the bar 15 that is formed with an opening to accomodate the pipe section 11 to prevent movement of the tanks and insure the tanks being held in their upright position.

Communicating with each tank is a pipe 16 which communicates with the pipes 17 and 18, through the union 19, there being provided a valve 20 within the pipes 16 to control the passage of oil from the tank, while the pipes 17 and 18 are provided with valves 21 and 22 to control the passage of fuel through the pipes 17 and 18. The lower ends of the pipes 17 and 18 communicate with the pipes 23 and 24 respectively, which pipes have connection with the vertical pipes 25 that support the burners proper 26, the burners 26 being positioned between the walls of the stove proper to supply the heating compartments of the stove with the necessary heat.

Each burner includes a body portion 27 formed with an inner wall 28, the inner wall being curved upwardly and formed with an opening 29 to permit fuel to flow from the pipe 25 associated therewith to the body portion or cup formed between the walls 27 and 28, where the same may be burned.

It might be further stated that openings 30 are formed in the bottom wall 12 to admit air to the stove and insure perfect combustion of the fuel. From the foregoing it will be obvious that the heat from the stove

may be controlled by lighting a sufficient number of burners of the stove.

If the temperature in a room is exceptionally cold, it will be obvious that all of the 5 burners should be lighted, but if the temperature is moderately cold, it is obvious that one or two burners should be lighted.

I claim:

1. An oil burning stove including an 10 outer wall and an inner wall, the walls being spaced apart to provide compartments, the upper ends of the walls being curved to provide heating chambers, oil burners supported within the compartments, and means for 15 supplying fuel to the oil burners.

2. An oil burning stove including an outer wall and an inner wall, the walls being spaced apart to provide compartments, said walls being formed with curved upper portions 20 providing heating chambers, burners disposed in the heating compartments, each of the burners including a cup and a pipe

disposed substantially centrally of the compartments, and means for supplying liquid fuel to the burners.

3. An oil burning stove including an outer wall and an inner wall, the walls being spaced apart to provide heating compartments, the walls being formed with curved portions at their upper ends to provide heating chambers, oil tanks supported adjacent to the upper portion of the stove, pipes in communication with the tanks and extending downwardly therefrom, said pipes extending inwardly and terminating within the compartments, and burners supported on the inner ends of the pipes.

In testimony that I claim the foregoing as my own, I have hereto affixed my signature in the presence of two witnesses.

JAMES T. RAY.
